FLAP OPENER FOR CARTONS

Arthur W. Lippmann and Edmund E. Lippmann,
Milwaukee, Wis., assignors to Lippmann Engineering Works, Milwaukee, Wis., a partnership

Application July 31, 1951, Serial No. 239,528

3 Claims. (Cl. 53—24)

1

This invention appertains to the filling of cartons with articles, and more particularly to means for carrying the cartons to and from a carton filling machine. The carton filling machine can be of any type but is preferably of the character shown in our pending application for patent, Serial Number 644,622, filed January 31, 1946, now U. S. Patent No. 2,579,237, patented December 18, 1951.

One of the primary objects of our present invention is to provide a novel and simple means for automatically opening the flaps of a carton as the carton reaches the filling station and for holding the flaps in their open position until the carton has been filled and is moved past the filling station.

Another salient object of the invention is the provision of an endless carrier having carton holding means thereon traveling in a step-by-step movement past a filling station, and a novel flat spreading, stationary shoe arranged for fully opening the side flaps and one end flap as the carton reaches the filling station, with means automatically operable by the endless carrier for opening the remaining end flap after this flap has passed the stationary shoe.

A further important object of the invention, is the provision of a novel flap spreading device for cartons which will be extremely durable and efficient in use, and one that can be manufactured and placed upon the market for use with a carton filling machine, at a minimum cost.

With these and other objects in view, the invention consists in the novel construction, arrangement and formation of parts, as will be hereinafter more specifically described and claimed, and illustrated in the accompanying drawings, in which drawings,

Figure 1 is a fragmentary top plan view of the carton conveyor, with the novel carton flap spreading means incorporated therewith, parts of the figure being shown broken away and in section to illustrate structural detail, one of the cartons being shown at the filling station with the side flaps and one end flap swung open.

Figure 2 is a fragmentary side elevational view of the carton conveyor, with the flap spreading means, parts of the figure being shown in section, the parts in section being taken on the line 2—2 of Figure 1, looking in the direction of the arrows.

Figure 3 is a transverse sectional view through the machine taken on the line 3—3 of Figure 2, looking in the direction of the arrows and showing the flap spreading shoe.

2

Figure 4 is a view similar to Figure 3, but taken on the line 4—4 of Figure 2, looking in the direction of the arrows and showing the finger for opening the end flap not affected by the shoe.

5 Referring to the drawings in detail, wherein similar reference characters designate corresponding parts throughout the several views, the letter C generally indicates an endless conveyor and F the novel flap spreading and opening means.

The conveyor C comprises a base frame, preferably formed from spaced parallel longitudinally extending channel beams 5 and 6. The channel beams are rigidly connected together in any desired manner, such as by transverse brace bars 7. Supporting standards 8 are rigidly secured to the beams 5 and 6 for supporting the beams at the desired height. Mounted for traveling movement on the frame is the endless carrier 9, which can consist of pairs of sprocket chains 10 trained around sprocket wheels 11. The sprocket wheels 11 are keyed or otherwise secured to a transversely extending shaft 12, rotatably mounted in bearings 13 mounted on the channel beams 5 and 6. The shaft 12 can be considered as a driven shaft for actuating the endless carrier 9. The pairs of sprocket chains 10 carry at equidistantly spaced points, carton gripping and carrying flights 14. The flights 14 embody upstanding lugs 15 and facing lugs are carried by each chain of the pairs of chains 10, so that a carton will be held adjacent to its opposite ends and at spaced points. The lugs 15 are formed on bases 16 which are riveted or otherwise secured to certain links of the sprocket chains, and it is to be noted that the bases extend a considerable distance beyond their attaching points to provide feet 17 which rest on the chains for preventing tilting of the lugs 15 on the chains. However, the construction is such that as the chains travel about the sprocket wheels 11, the lugs can easily move about the contour of the sprocket wheels.

As stated, the cartons are held by the lugs 15 and these cartons are indicated by the reference character 18. The cartons are of a type now commonly found on the market and can be formed from any material, such as corrugated board, and in setting up the cartons one end thereof is closed and the other end is left open. Each open end of the carton, includes side flaps 19 and end flaps 20 and 21, and these flaps are manually pulled outwardly to a position shown in the left hand side of Figures 1 and 2.

To hold the cartons against lateral shifting 55 on the conveyor and to hold the closed ends of

the cartons against opening movement in case they are freshly sealed, a longitudinally extending guard rail 22 is provided. This guard rail 22, is rigidly fastened to the channel beam 5 by spaced supporting arms 23.

The conveyor is operated in any approved manner in a step-by-step fashion, past a filling station 24, and the step-by-step movement of the conveyor is timed so that the conveyor will stop with the open end of a carton facing the filling station for a certain interval of time.

At the filling station 24 is disposed a filling throat or chute 25 carried by a supporting table 26. The table and the chute or throat are arranged transversely of the line of travel of the conveyor and at one side thereof. The table 26 is carried by standards 27, which are rigidly fastened to the channel beam 6. The chute or throat 25 corresponds in cross section to the shape and size of the carton in cross section 20 and the chute or throat includes side walls 28 and 29, and a bottom wall 30. The side wall 28 and the bottom wall 30 can be formed together and the side wall is secured to a reinforcing web 31 which is also bolted or otherwise fastened to the table 26. The side wall 29 is securely fastened to a reinforcing web 32 which is adjustable within certain limits on the table 26. This can be accomplished by slotting the base of the web 32, as at 33, for the reception of headed set screws 34, which pass through the slots and into the table.

During the travel of the conveyor, and as a carton approaches the filling station, the flaps 19 and the flap 20 are forced back toward the body of the carton in a novel manner so that when the carton reaches the filling station, the flaps will be out of the way to receive the articles being moved into the carton. The means for opening out the flaps includes a novel flap spreading shoe 35, which projects laterally from the table 26 toward an approaching carton and in the path of the projecting flaps of a carton. The shoe includes upper and lower flap spreading rails 36 and 37. The rails 36 and 37 incline inwardly toward one another, and are connected together by an outwardly inclined plate 38. The plate 38 lies substantially at a point intermediate the top and bottom walls of a carton and between the side flaps 19 thereof.

Now considering that a carton 18 is approaching the filling station, the leading pointed terminal of the shoe 35 will initially engage the end flap 21, see Figures 1 and 2, and move this flap to the left, or over the end of the carton. Upon continued movement of the conveyor and carton, the side flaps 19 will engage and travel over the inclined rails 36 and 37 which will effectively swing back or out, these flaps and when the flap 20 reaches the plate 38, this flap will be moved to the left and away from the open end of the carton. When the carton reaches the filling station, the flaps 19 will be held by the rails in their spread position, as with the flap 20, but the flap 21 will have moved past the shoe and is left free. Means is provided for automatically engaging and pulling back the flap 21 to its wide open spread position, so that articles can be effectively moved into the carton.

The means for pulling open the flap 21 includes a reciprocating rod 39 guided in its traveling movement by rollers 40 mounted on the rail 36. The inner end of the rod 39 has formed thereon a depending leg 41, and secured to this leg is an inwardly directed flap engaging finger 42. This

rod 39 is moved back and forth in the following manner. Rigidly secured to the channel beam 6 adjacent to the shaft 12 is a bracket 43. Rockably mounted upon the bracket is a bell crank 44. The outer end of one arm of the bell crank is operatively connected, as at 45 to the rod 39. The outer end of the other arm of the bell crank has rotatably mounted thereon a roller 46 disposed in the path of a crank 47, keyed or otherwise secured to the shaft 12. During rotation of the shaft 12 and upon each revolution thereof, the crank 47 will engage the roller 46 and rock the crank to the left (see Figure 2), and the finger 42 will be moved into the throat or chute past the flap 21. A contractile coil spring 48 connects the bar 39 with the bracket 43 and the spring is placed under tension, when the bar 39 moves to the left. Consequently, as soon as the crank 47 rides past the roller 46, the spring 48 will move the bar 39 back to its normal position to the right. The finger 42 will engage the inner surface of the flap 21, and hence pull this flap to a wide open position.

It is again pointed out that the parts are so timed that when a carton reaches the filling station, the finger 42 will swing back the carton flap 21 so that the carton can be filled, and after the lapse of a certain interval of time, the carton will be carried past the filling station and the filled carton can then be removed from the conveyor and the flaps sealed.

From the foregoing description, it can be seen that I have provided a very simple means for spreading outwardly, the flaps of a carton to facilitate the loading of a carton with the desired articles.

Changes in details may be made, without departing from the spirit or the scope of this invention, but what we claim as new is:

1. A device for spreading out the sealing flaps of cartons, as the cartons reach a filling station comprising an endless conveyor traveling past a filling station, means on the conveyor for supporting cartons with the flaps of the cartons at one side of the conveyor projecting outwardly from the bodies of the cartons, a filling throat at the filling station disposed at one side of the conveyor and transversely thereof, a shoe projecting laterally from one side of the throat extending longitudinally of the conveyor and including side flap spreading rails inclining toward one another and disposed in the path of the flaps during movement of the conveyor, an inclining end flap spreading plate connecting the outer ends of the rails, a movable finger for spreading out a carton end flap, means for operating said finger including a reciprocating rod carried by the finger, spring means urging the rod and the finger in one direction away from a carton, and a conveyor actuated crank periodically actuating the rod toward a carton against the tension of said spring means.

2. A device for spreading out the sealing flaps of cartons, as the cartons reach a filling station, comprising an endless conveyor, means on the conveyor for holding cartons at spaced points, a frame, a filling throat at one side of the conveyor, the cartons on the conveyor having open flaps at one end for movement past the throat, the cartons having their opposite ends sealed, a guide rail rigidly carried by the frame engaging the sealed ends of the cartons to prevent lateral shifting of the cartons on the conveyor, a flap spreading shoe rigidly carried by the frame including upper and lower side flap spreading rails

adapted to engage the side flaps of the carton as the carton approaches the throat, said rails including inwardly directed inclined portions, an end flap opening plate rigidly connecting said portions together so that upon movement of a carton past the shoe to the throat the side flaps will be spread by the rails and one end flap will be spread by the plate, means for spreading the other end flap when the carton reaches the throat, said means for spreading out the last mentioned end flap of a carton including a reciprocating bar mounted on the frame, a laterally projecting finger on the bar movable past the open end of the carton for engaging the last mentioned end flap, spring means normally holding the bar and finger away from the throat and a carton disposed at the throat, a crank arm rockably mounted on the frame, means operatively connecting the crank arm to the bar, a crank secured to and rotatable with the shaft for periodically actuating the bell crank.

3. A device for spreading out the sealing flaps of cartons, as the cartons reach a filling station comprising an endless conveyor traveling past a filling station, means on the conveyor for supporting cartons with the flaps of the cartons at one side of the conveyor projecting outwardly

15

from the bodies of the cartons, a filling throat at the filling station disposed at one side of the conveyor and transversely thereof, a shoe projecting laterally from one side of the throat extending longitudinally of the conveyor and including side flap spreading rails inclining toward one another and disposed in the path of the flaps during movement of the conveyor, an inclining end flap spreading plate connecting the outer ends of the rails, and a movable finger on the other side of the throat and movable in front of the throat for spreading out an end flap of the carton as the carton reaches the filling throat.
